UNITED STATES PATENT OFFICE

2,235,946

ATOMIZER

Alfred F. Reilly, North Attleboro, Mass., assignor
to Evans Case Company, a corporation of
Massachusetts

Application May 23, 1940, Serial No. 336,847

8 Claims. (Cl. 299—96)

The present invention relates to an atomizer in which there is a receptacle containing a liquid to be atomized provided with an opening which is above the normal level of the liquid.

5 In such devices when the atomizer is inverted or turned the liquid may run out of its receptacle and possibly into some other portion of the apparatus. The purpose of the present invention is to provide means for preventing this exit of the 10 liquid. To this end means are provided which tend to automatically close the outlet from the liquid chamber when the apparatus is inverted or moved from its normal operating position.

The locking device of the present invention may 15 be applied to atomizers of many different forms and types. In order to disclose the invention but not as a limitation on the invention one form of apparatus to which it may be applied is illustrated in the accompanying drawing in which 20 Figure 1 is a transverse vertical section of one specific type of atomizer in normal position; Fig. 2 is a similar transverse, fragmentary vertical section in the inverted position.

The liquid chamber 10 is shown as provided 25 with a pipe 11 entering its upper end. The pipe 11 communicates at 12 with a bellows 13 or other means for supplying air under pressure so that in the normal position air under pressure may be placed upon the top of the liquid in the tank 30 10. From the liquid chamber 10 and extending upwardly through the air tube 11 and preferably centrally disposed therein is a liquid pipe 14 through which liquid may be withdrawn and atomized. Surrounding and carried by the end 35 35 of the tube 14 in the liquid chamber is a plug 15. The lower end 16 of the liquid pipe 14 is spread or splayed so as to limit the downward movement of the plug 15 as illustrated in Fig. 1. In its normal position the plug 15 rests against 40 the splayed end 16 and is further from contact with the lower end of the air pipe 11. There may be a washer 17 or other contact device on the upper end of the plug 15. The plug 15 may be made relatively heavy and is free to slide on the 45 pipe 14 so that when the device is inverted as illustrated in Fig. 2 the plug 15 will ride on the tube 14 and bring the washer 17 in contact with the lower end of the air pipe 11 and thus form a seal to prevent the passage of liquid from the 50 liquid chamber 10 into the air pipe 11. Small atomizers are frequently abused or roughly handled. They are frequently packed in bags for travel and the like. The present device provides

a means by which gravity alone may automatically cause the lock 15 to seal the liquid chamber against outlet of liquid. It will be understood, of course, that the liquid pipe 14, as is usual in atomizers, is so small that there will be 5 substantially no leakage of liquid through it.

The proportions, sizes, shapes and other details of the apparatus illustrated are not essential to the present invention which may be embodied in other types of apparatus. 10

I claim as my invention:

1. In an atomizer having a liquid chamber with an opening for the inlet of air under pressure and a liquid outlet tube passing through the opening, a plug guided on the tube for closing the opening. 15

2. In an atomizer having a liquid chamber with an opening for the inlet of air under pressure and a liquid outlet tube passing through the opening, a plug surrounding the tube and slidable 20 thereon for closing the opening.

3. In an atomizer having a liquid chamber with an opening for the inlet of air under pressure and a liquid outlet tube passing through the opening, means for automatically preventing liquid going 25 out through the opening when the device is inverted.

4. In an atomizer having a liquid chamber with an opening for the inlet of air under pressure and a liquid outlet tube passing through the opening, means operated by gravity for closing 30 the opening when the device is inverted.

5. In an atomizer having a liquid chamber with an opening for the inlet of air under pressure and a liquid outlet tube passing through the opening, a plug surrounding the tube and slidable 35 thereon by gravity when the device is inverted for closing the opening.

6. In an atomizer having a liquid chamber with an opening for the inlet of air under pressure and a tube passing through the opening, a plug guided 40 on the tube for closing the opening.

7. In an atomizer having a liquid chamber with an opening for the inlet of air under pressure and a tube passing through the opening, a plug 45 surrounding the tube and slidable thereon for closing the opening.

8. In an atomizer having a liquid chamber with an opening for the inlet of air under pressure and a tube for the outlet of liquid passing through 50 the opening, a plug slidably supported by the tube for closing the opening.

ALFRED F. REILLY.
